United States Patent Office

Des. 207,781
Patented May 30, 1967

207,781

BIRD FOOD PENDANT

Henry E. Lowe, Jr., Cassopolis, Mich., assignor to Lowe's,
Inc., Cassopolis, Mich., a corporation of Michigan

Filed May 10, 1965, Ser. No. 85,185

Term of patent 14 years

(Cl. D31—2)

FIG. 2

FIG. 1

FIG. 4

FIGURE 1 is a front elevational view of a bird food pendant embodying the present design, and illustrating in two areas the general surface appearance of the device, including various types of seeds;

FIGURE 2 is a top plan view of the bird food pendant shown in FIGURE 1;

FIGURE 3 is a side elevational view of the bird food pendant shown in the preceding figures; and

FIGURE 4 is a bottom plan view of the device.

I claim:

The ornamental design for a bird food pendant, as shown and described.
